UNITED STATES PATENT OFFICE

MAX PAUL ERNST HOHN, OF DRESDEN, GERMANY, ASSIGNOR TO "UNIVERSELLE" CIGARETTENMASCHINEN-FABRIK J. C. MÜLLER & CO., OF DRESDEN, GERMANY

FEEDING OF CIGARETTES TO PACKING MACHINES

Application filed February 24, 1931, Serial No. 517,990, and in Germany September 10, 1930.

In the case of cigarettes of oval, i. e., flattened cross-section, it is already known, for the purpose of turning incorrectly disposed cigarettes during feed to the packing machine, to employ feelers, pawls, grippers or the like, which engage with the front edge of the upper lap of the seam to turn the cigarette either directly or to release a mechanical or electrical apparatus which effects the turning. This method of turning can only be used, however, with flattened cigarettes, which may be fed to the feeler in the flat position, and in which the seam always lies in the middle of a flat side.

The present invention relates to a device, by means of which round cigarettes also may be so adjusted that the seam lies underneath or the superscription lies on the top. A feeler of the type specified cannot be used with such cigarettes, because the cigarettes are fed in very many different positions, so that the seam occasionally also lies at the side, where it cannot be engaged by the feeler. In order now to be able to adjust round cigarettes also, there is provided according to the invention a friction surface along which the cigarettes are conveyed and which acts upon the surface of the cigarette and rotates it until its seam engages with a pawl mounted on the bottom of the conveying apparatus. This pawl is so arranged that on its engaging the seam, the cigarette will have the correct position. Preferably, instead of a single friction surface, a plurality of friction surfaces are arranged in succession, so that they may be made lighter and damage to the cigarettes may be avoided.

A constructional form of the invention is shown by way of example in the accompanying drawings in which

Figure 1 is a front elevation,

Figure 2 is a side elevation.

The round cigarettes *a* are fed on a conveying apparatus which in the example shown is in the form of a chain and which has links *b* provided with trough-shaped recesses for carrying the individual cigarettes. The links *b* are provided with cut-out parts *c*, in which are inserted resilient pawls *d*. These pawls each consist of a flat strip spring, secured by

means of a screw *e* to the chain link *b* and carrying on its free end a block *f* or the like, which is provided with an inwardly directed sharp edge. A set screw *g* serves to adjust the spring, and with it the knife-edge of the block to the correct height. The part of the block adjoining the knife-edge is cut away upwardly so as to fit exactly the round form of the cigarette and so that the knife-edge can come into engagement with the seam of the cigarette when the latter is rotated about its axis. Above the path of the chain conveyor for the cigarettes, friction surfaces *h* are provided on rails *h*, which are secured to the machine frame in any manner, for example by means of the screws *i*. The said friction surfaces are rotatable about pivots *m*, and the pivots are located offside of the centre, so that the rear part of the friction surfaces in the direction of movement of the cigarettes has the greater weight and will tilt downwardly. In the rails *h* there are provided stop screws *n*, the adjustment of which determines the inoperative position of the friction surfaces.

The mode of operation of the device is accordingly as follows:

The cigarettes are brought into any position, just as they come from the machine, into the individual grooves of the conveyor chain, and are then carried beneath the friction surface *h*. The surfaces are lifted slightly by the cigarettes as they pass, and owing to the friction between the cigarette and friction surface, the cigarettes are set in rotation. The cigarettes are rotated by the successive surfaces until the front edge of the seam comes into engagement with the knife-edge of the block *f* of the pawl *d*. As soon as this has taken place, the cigarette is held fast, and the friction of the following friction surfaces is no longer effective to produce further rotation. Thus, the cigarettes will assume their correct position when they have passed beneath the friction surfaces.

Of course, any number of friction surfaces may be provided. They may be mounted, as in the example shown, on both sides of the cigarette, or on one side or in the middle. The purpose of subdividing the friction surfaces is to enable them to be made

lighter and to enable the engagement with the cigarettes to be accurately regulated. Constructionally of course, the apparatus may be made different. Thus, conveyor drums 5 may be used instead of the conveyor chains for the cigarettes, or instead of the double arrangement of pawls on both sides, only one pawl may be provided in the middle, or the pawl may be constructed in any other 10 manner.

I claim:

1. An apparatus for adjusting cigarettes into the face position comprising in combination a friction surface, a conveying apparatus carrying the cigarettes with their free lying surface along said friction surface thereby rotating them on said conveying apparatus and stops provided on the conveying apparatus and engaging the face 15 of the seam of the rotating cigarettes for the purpose to stop their rotation.

2. An apparatus for adjusting cigarettes into the face position according to claim 1, characterized by said stops having the form of 20 plurality of friction surfaces arranged side by side.

3. An apparatus for adjusting cigarettes into the face position according to claim 1, characterized in that the friction surface arranged 25 above the feed path of the cigarettes is constructed in the form of a double lever having a pivot offset from its centre so that the heavier end descends into the path of the cigarettes and is lifted by them when coming 30 in frictional engagement.

4. An apparatus for adjusting cigarettes into the face position according to claim 1, characterized by the arrangement of a plurality of friction surfaces arranged above the 40 feed path of the cigarettes and being constructed in the form of double levers having pivots offset from their centre so that the heavier ends descend into the path of the cigarettes and are lifted by them when coming 45 in frictional engagement.

5. An apparatus for adjusting cigarettes into the face position according to claim 1, characterized by said stops having the form 50 of resilient pawls.

6. An apparatus for adjusting cigarettes into the face position according to claim 1, characterized by said stops having the form of 55 resilient pawls and carrying on their free ends blocks cut away in accordance with the shape of the cigarettes and having a knife edge engaging with the seam.

7. An apparatus for adjusting cigarettes into the face position, comprising in combination a plurality of friction surfaces, a conveying apparatus carrying the cigarettes with their free lying surface along said friction surfaces thereby rotating them on said conveying apparatus and stops provided on the conveying apparatus and engaging the 60 face of the seam of the rotating cigarettes 65

for the purpose to stop their rotation, said stops having the form of resilient pawls.

8. An apparatus for adjusting cigarettes into the face position comprising, in combination, a plurality of friction surfaces, a conveying apparatus carrying the cigarettes with their free lying surface along said friction surfaces thereby rotating them on said conveying apparatus and stops provided in the conveying apparatus and engaging the 70 face of the seam of the rotating cigarettes for the purpose to stop their rotation, said stops having the form of resilient pawls and carrying on their free ends blocks cut away in accordance with the shape of the cigarette and having a knife edge engaging with the seam.

In testimony whereof I have affixed my signature.

MAX PAUL ERNST HOHN.
